(57) **CLAIM**

The ornamental design for a fishing reel, as shown and described.

DESCRIPTION

FIG. 1 is a right front perspective view of a fishing reel showing my new design;

FIG. 2 is a left front perspective view of the device shown in FIG. 1;

FIG. 3 is a rear elevation view of the device shown in FIG. 1.

FIG. 4 is a front elevation view of the device shown in FIG. 1.

FIG. 5 is a right end elevation view of the device shown in FIG. 1.

FIG. 6 is a left end elevation view of the device shown in FIG. 1.

FIG. 7 is a top plan view of the device shown in FIG. 1; and, FIG. 8 is a bottom plan view of the device shown in FIG. 1. The dash lines form no part of the design and are included for environmental purposes only.
